Application July 7, 1933, Serial No. 679,429

10 Claims. (Cl. 101—282)

This invention relates to gearing and more particularly to that type of gearing which is adapted to be employed in the bed motions of printing presses.

5 The principal object of the invention is the provision of novel and improved gearing of this character which is compact, efficient in operation, and well adapted to positively and easily reciprocate the bed of a printing press to which is may be applied.

10 As is well-known in the art, the bed motion of a printing press of the horizontally reciprocating bed type generally embodies means for reciprocating the bed at a uniform rate of speed through the intermediate and greater portion of each 15 stroke, and further means for gradually retarding, reversing, and accelerating the movement of the bed at the end portions of each stroke in order to avoid a sudden reversal of the bed and a consequent shock to the bed frame, driving gear, and printing mechanism. This gearing is at best somewhat complicated, and in prior mechanisms of this type, exceedingly large gears or pinions have been employed. These gears have been of 20 considerable vertical and longitudinal extent and have occupied considerable space within and adjacent to the frame of the press. In presses of large capacity, the weight of these gears has also been a factor to be considered in providing adequate balanced support for the bed motion.

25 By means of the present invention, however, there is provided a bed motion which is exceedingly compact in arrangement, embodying in its construction gears or pinions of substantially no greater diameter than that of the impression cylinder of the press, thus rendering both the installation and operation of the gearing easy, and distributing and materially reducing the weight of the moving parts.

30 In its preferred embodiment, the invention contemplates the application of this novel gearing to a printing press of the two-revolution type which comprises an impression cylinder and a reciprocating bed adapted to execute a forward printing stroke and an idle stroke in the reverse direction. Although especially applicable to this type of press, the invention in its broader aspects, however, is not limited thereto but may be employed 35 in connection with various other types of printing presses and mechanical devices designed to execute similar movements.

40 A further object of the invention is the provision of a novel form of alternating rotary gearing which is featured by compactness and simplicity of construction.

45 Other objects and features of novelty will be apparent from the following specification when read in connection with the accompanying drawings, in which one embodiment of my invention is 50 illustrated by way of example.

In the drawings:

Figure 1 is a partly diagrammatic view in side elevation of a two-revolution printing press to which my improved gearing has been applied, a portion of the nearer side frame being broken away in order to more clearly illustrate certain parts of the gearing; 5

Figure 2 is a plan view of my novel bed motion gearing applied to the press frame, with the superstructure of the press removed for the sake of 10 clearness of illustration;

Figure 3 is a detail view in horizontal cross-section on a somewhat larger scale taken on line 3—3 of Figure 4;

Figure 4 is a view in front elevation of the press, 15 portions of the supporting frame and of the operating mechanism being broken away for the sake of clearness; and

Figure 5 is a diagram illustrating the synchronization of operation of the more important elements of my improved bed motion. 20

The supporting base of the press, designated generally by the numeral 10, comprises the side frame members 11 and 12 and the tie frame 15 which is preferably of metal and cast in a single 25 piece. The tie frame casting 15 is approximately H-shaped in plan, having a substantially centrally located longitudinal web 16, an end web 17, and a transverse web 18 which is disposed adjacent the mid-portion of the press. The ends 30 of the transverse members 17 and 18 are rigidly secured to the side frames 11 and 12 by suitable means.

An impression cylinder of conventional type is indicated at 20 and is mounted on a shaft or 35 axle 19 which has its bearings in the usual vertically disposed members 21. The press, of course, is provided with a feed table, such as is shown at 22, and a delivery mechanism illustrated at 23 in Figure 1 of the drawings. The inking mechanism is shown at 24 and is connected to the driving mechanism by any suitable or conventional means. The cylinder gear 25 is also rotated by this driving mechanism as will be described. The reciprocating type bed 30 carries the usual form 31 and is mounted upon the roller frames 32 which travel in the parallel tracks or ways 33.

The type bed is provided with a main driving rack 35 which is in constant mesh with the driving pinion 36 carried by the oscillating shaft 37, the actuation of which will be described herein-after. Because of the location of shaft 37, that is to say, substantially in the vertical plane containing the axis of the impression cylinder, rack 55 35 does not need to project at one end of the bed in order to remain in contact with its driving gear 36. Expressed in another way, the axis of shaft 37 is located substantially directly below the transverse center line of the bed when the 60

latter is in mid position. Reversing racks 38 and 39 are provided at the respective ends of the type bed 30 and are alternately engageable by the reversing segment 40. The operation of this reversing mechanism is substantially as set forth in my prior Patent No. 1,777,092 and will be described in detail further along in the present specification.

Power from a suitable source is supplied to the operating mechanism of the press by means of a belt (not shown) which is trained around the pulley 42 keyed to one end of the shaft 43 which has its bearings, as at 44 and 45, in the side frame 11 and the central web 16 of the tie frame 15 respectively. A pinion 46 is secured to the shaft 43 intermediate its length and meshes with a larger gear 47 which is rigidly secured upon the shaft 48 which also has its bearings in the supporting base as at 49 and 50. Also secured upon the shaft 48, preferably at its outer end, is the pinion 51. A pair of pinions 52 and 53, each of the same diameter as the cylinder gear 25, are disposed in intermeshing relation, and the gear 51 is adapted to mesh with pinion 52. The pinions 52 and 53 are secured upon the shafts 54 and 55 respectively, both of which are mounted for rotation in the supporting base 10 in suitable bearings, as indicated at 56, 57, 58, and 59. As clearly shown in Figure 2, the gear train 51, 52, 30 and 53 is preferably arranged outside of and 35 parallel with one of the side frames 11.

In the arrangement illustrated and described, it will be understood that the pinions 52 and 53 rotate at a constant rate of speed but in opposite directions, the directions of such rotation being indicated by the arrows 60 and 61 in Figure 1. Gear segments 62 and 63 are secured upon the shafts 54 and 55 respectively so as to rotate in different planes, as clearly shown in Figure 2 40 of the drawings. These segments are, in the particular application of the invention disclosed, of an angular extent of 240°, are of somewhat smaller diameter than their associated pinions 52 and 53, and are located between these pinions and 45 the side frame 11 of the press.

For the purpose of providing an alternating connection between the oscillatable bed driving shaft 37 and the gear segments 62 and 63, a sliding gear 65 is mounted upon the shaft 37, being 50 splined for rotation therewith, as at 66, but free to move longitudinally thereof for a limited distance. The sliding gear 65 is secured to or formed integrally with the sleeve 67 which surrounds the shaft 37 and has a bearing at 68 in 55 the side frame member 11. The inner end of the sleeve 67 is provided with a groove 69 within which is disposed the pin 70 carried by one end of the lever 71 which is fulcrumed in the bracket 72 carried by the frame member 11. The opposite end of the lever 71 is provided with a pin 60 and roller projection 73 which is guided in the cam groove 74 formed in the constantly rotating cam member 75. The cam 75 is carried by a shaft 76 rotatably mounted in suitable bearings in 65 the base frame and driven preferably from the shaft 54 by means of the gears 77 and 78. The ratio of the gears 77 and 78 is such that the cam 75 makes one complete revolution for each two revolutions of the shaft 54 and consequently of 70 the gears 52 and 53 and their associated segments 62 and 63.

The details of construction of the reversing mechanism for the type bed 30 will now be described. The reversing segment 40, already referred to, is carried by the lever 80 which is ful-

crumed approximately centrally of its length upon a stationary bearing sleeve or bushing 81 through which the bed drive shaft 37 extends. The opposite end of the lever 80 is pivotally connected as at 82 with the pitman or cross-head connection 85, which is driven from the cross-head 86 to which it is connected as at 87. This cross-head 86 is adapted to reciprocate horizontally in the guides 91 (Figure 2) with simple harmonic motion. This cross-head forms a part of the familiar Scotch yoke. The cross-head 86 is provided with a vertical slot 88 within which the block 89 of the crank 90 is adapted to move, the block 89 being pivotally mounted upon the crank arm 90. The crank arm 90 is carried by the shaft 43, which is designed to make three revolutions during each cycle of reciprocation of the bed, this being governed by the ratio of the gears 51, 52, etc. Thus it will be seen that the segment 40 will make three complete oscillations for each 20 cycle of operation of the press.

The impression cylinder gear 25, carried by the cylinder axle 19, is driven from the pinion 53 through the intermediate gears 96 and, as indicated heretofore, is of the same diameter as the 25 two pinions 52 and 53.

The operation of my improved bed motion will now be described. As already explained, the driving segments 62 and 63 are of an angular extent of 240° and make two revolutions at a uniform 30 angular velocity for each complete cycle of movement of the bed of the press. The bed driving shaft 37 is alternately engageable with the segments 62 and 63 by means of the sliding gear 65 which is moved from the plane of one of the segments to the plane of the other during the hiatus provided by the gaps in these segments. This movement of the sliding gear 65 is effected twice during the press cycle by means of the cam 75. Each of the segments 62 and 63 is adapted to 40 move the type bed 30 at a constant speed through the mid-portion of its printing and idle strokes respectively, and since the angular extent of the segments is 240°, they are operative for two thirds of each stroke. 45

The segment 63 may be designated the printing stroke segment since it is employed to effect the movement of the type bed during the contact of the type form with the matter carried by the impression cylinder. The segment 62 is therefore the idle stroke segment since it is operatively connected with the drive shaft 37 and driving pinion 36 during the return or idle stroke of the bed. At the end of each stroke the printing and idle segments are, of course, disengaged, and 55 the retarding, reversal, and acceleration of the bed are effected by means of the reversing segment 40, which alternately engages the reversing racks 38 and 39 for this purpose.

Taken in the sequence in which these driving 60 means are effective, beginning with the position shown in Figure 1 of the drawings, a complete cycle of operation will be explained. In Figure 1 the bed is at its extreme left-hand position. The reversing segment 40 has just completed the retarding and reversing movement of the bed in engagement with the reversing rack 39. The cross-head 86 is at its extreme right-hand dead center position and about to be moved by the crank 90 in passing through the upper half of its 70 orbit. Both of the segments 62 and 63 are out of engagement with the driving shaft gear 65 during this reversal movement. The segment 40 next moves toward the right and is in effective driving engagement with the reversing rack 39 75

for the initial one sixth of the time of its printing stroke. Then the printing segment 63 engages the sliding gear 65 which has been brought into its plane through the action of cam 75 and accomplishes the major portion of the printing stroke.

Upon disengagement of the segment 63 with the gear 65, the latter is moved into the plane of the idle segment 62 while the reversing segment 40 engages the rack 38 and, during the retarding portion of the printing stroke, reverses the movement of the bed and starts the bed on its idle or reverse stroke at accelerating speed. Then the idle stroke segment 62 engages the sliding gear 65, causing the drive gear 36, through the main rack 35, to move the bed 30 through the central two thirds of its idle stroke, whereupon the reversing segment 40 again engages the rack 39 and retards the bed preparatory to the next reversal thereof.

As heretofore explained, the reversing segment 40 makes six movements during a complete cycle of the press, and naturally two of these movements are idle ones which occur during the effective operation of the printing and idle segments 63 and 62.

The synchronous sequential operations of the more important elements of the bed motion are graphically illustrated in Figure 5 of the drawings. From this diagram it will be readily seen that the bed of the press, the movement of which is depicted by Graph I, executes a printing stroke indicated by the line *af* and a reverse idle stroke indicated by the line *fk*. As has been already explained, the printing gear segment 63 makes two revolutions for each cycle of the press, indicated by the distance *ak*. The Graph II shows the operative and inoperative portions of the printing segment cycle. The operative portion indicated between the points *b* and *e* represents two thirds (240°) of one revolution. During the remainder of this cycle, indicated by the dotted lines, the other actuating members are operative as indicated in the further graphs. Graph III shows between *g* and *j* the operative phase of the idler gear segment.

In Graph VI the cam 75 is shown in projected form. It will be noted that immediately after the completion of the effective portion of the printing stroke cycle at *e* the cam track shifts laterally to carry the sliding gear 65 over into the plane of the idler segment. Then, of course, after the completion of the idler stroke at point *j*, the cam again moves the sliding gear back to the plane of the printing segment.

Graph V represents the three revolutions of the crank 90 which actuates the reversing segment 40, and in the Graph IV the resulting movements of the reversing segment 40 during the press cycle are shown. Specifically, the reversing segment makes six movements upon its pivot during the cycle, namely, *ac*, *cd*, *df*, *fh*, *hi*, *ik*. During a portion of the stroke *ac*, the reversing segment operates in mesh with the reversing rack 39 on the type bed to initiate the printing stroke; during the return oscillation *cd*, the reversing segment is ineffective as regards moving the type bed; and in the latter portion of the stroke *df* and the early portion of the stroke *fh*, the reversing segment serves to retard, reverse, and accelerate the type bed while in mesh with the rack 38. The reversing segment executes another idle stroke in the right-hand direction, shown at *hi*, and during the latter half of the stroke *ik* it is again in mesh with the rack 39, serving at this

point to retard and eventually reverse the movement of the type bed at the end of its idle stroke.

It will be apparent that the arrow heads in the chart indicate directions of movement; in the case of reciprocating or rocking members, either toward the left or the right hand; and in the case of rotation, either clockwise or counter-clockwise, as viewed in Figure 1.

Although in the preferred embodiment of my invention the main driving segments are of 240° extent and the reversing segment operates during the remaining 120° of rotation of those segments, it will be realized that the arcuate length of the main segments may be varied and, by appropriate alterations in the gearing, the period of effective engagement of the reversing segment may be increased or diminished accordingly.

It will be understood that various other changes and modifications can be made in the embodiment illustrated and described herein without departing from the scope of the invention as defined by the following claims.

Having thus described the invention, what is claimed as new and desired to be secured by Letters Patent is:—

1. A bed motion for a printing press of the two-revolution type provided with a frame and a reciprocating bed thereon adapted to execute a forward printing stroke and a reverse idle stroke, including, in combination, a pair of gear segments of at least 240° extent rotatively mounted adjacent each other on the frame, the axes of said segments being in the same horizontal plane, one segment being located next to the frame and the other one gear width therefrom, means for rotating said segments in opposite directions at the same constant angular velocity at the rate of two revolutions for each complete cycle of reciprocation of said bed, and means alternately driven by said segments and operatively connected with said bed for effecting reciprocation of the same at a uniform velocity for more than one-half of each stroke.

2. A bed motion for a printing press of the two-revolution type provided with a frame and a reciprocating bed thereon adapted to execute a forward printing stroke and a reverse idle stroke, including, in combination, a pair of gear segments of at least 240° extent rotatively mounted adjacent each other on the frame, the axes of said segments being in the same horizontal plane, one segment being located next to the frame and the other one gear width therefrom, means for rotating said segments in opposite directions at the same constant angular velocity at the rate of two revolutions for each complete cycle of reciprocation of said bed, means alternately driven by said segments and operatively connected with said bed for effecting reciprocation of the same at a uniform velocity for more than one-half of each stroke, and means located within the frame for reversing the movement of said bed at the end of each stroke.

3. A bed motion for a printing press of the two-revolution type provided with a reciprocating bed adapted to execute a forward printing stroke and a reverse idle stroke, including, in combination, a pair of gear segments rotatively mounted adjacent each other on the press with their axes in substantially the same horizontal plane, means for rotating said segments in opposite directions at the same constant angular velocity, at the rate of two revolutions for each complete cycle of reciprocation of said bed, means

alternately driven by said segments and operatively connected with said bed for effecting reciprocation of the same at a uniform velocity for more than one-half of each stroke, said last 5 named means comprising a rack secured to said bed, a pinion continually in mesh with said rack, a shaft on which said pinion is secured, said shaft being supported substantially directly below the transverse center line of the bed when in mid 10 position and with its axis in substantially the same horizontal plane as the axes of said segments, and another pinion on said shaft adapted to alternately mesh with said gear segments.

4. A bed motion for a printing press including, 15 in combination, a pair of gear segments rotatively mounted adjacent each other on the press and disposed in separate planes, means for rotating said segments in opposite directions at the same constant angular velocity, a gear operatively connected with said bed for effecting its reciprocation at a uniform velocity for more than one-half of each stroke, and means for moving said gear from the plane of one of said segments to the plane of the other of said segments for alternating 20 engagements therewith the axes of said gear and gear segments being in substantially the same horizontal plane.

5. In a reciprocating bed motion the combination with a bed, of gearing for driving said bed 30 in alternate opposite directions, comprising means for moving said bed through the major portion of the stroke thereof, comprising a pair of oppositely rotating gear segments of an angular extent of 240°, a gear operatively connected 35 with said bed, the axes of said gear and gear segments being in substantially the same horizontal plane, means for automatically engaging said gear alternately with said segments, means for effecting the reversal of said bed at the end of 40 each stroke comprising an oscillating reversing segment adapted for intermittent engagement with said bed, a Scotch yoke transmission mechanism, a pitman connecting said segment with said mechanism, and common driving means for 45 said first named segments and said mechanism.

6. In a printing press provided with a supporting frame, a reciprocating type bed, and a rotary impression cylinder, in combination, driving mechanism comprising a pair of intermeshing 50 pinions, means for driving said pinions in opposite directions at the same constant angular velocity, a gear segment associated with each of said pinions and partaking of the same movements as its associated pinion, the two segments 55 occupying different planes, an impression cylinder gear of the same diameter as said pinions, gearing connecting said cylinder gear with one of said pinions, a gear operatively connected with said type bed for effecting its reciprocation at a 60 uniform velocity for more than one-half of each stroke, and means for moving said gear from the plane of one of said segments to the plane of the other of said segments for alternating engagements therewith.

65 7. In a printing press provided with a supporting frame, a reciprocating type bed, and a rotary impression cylinder, in combination, driving mechanism comprising a pair of parallel shafts carried by said frame, a pair of intermeshing pinions disposed exteriorly of said frame and each carried by one of said shafts, means for driving said pinions in opposite directions at

the same constant angular velocity, a gear segment of 240° of angular extent mounted upon each of said shafts between said frame and said pinions and partaking of the same movements as its associated pinion, the two segments 5 occupying different planes, an impression cylinder gear of the same diameter as said pinions, gearing connecting said cylinder gear with one of said pinions, a gear operatively connected with said type bed for effecting the major portion of 10 its reciprocation, and means for moving said gear from the plane of one of said segments to the plane of the other of said segments for alternating engagements therewith.

8. In a printing press, in combination, a supporting frame, a reciprocating type bed thereon, driving mechanism for said bed including a pair of parallel shafts carried by said frame, a pair of intermeshing pinions disposed exteriorly of said frame and each carried by one of said shafts, 15 means for driving said pinions in opposite directions at the same constant angular velocity, a gear segment of 240° angular extent mounted upon each of said shafts between said frame and said pinions and partaking of the same movements as its associated pinion, the two segments 20 being disposed in different planes, a gear operatively connected with said type bed for effecting the major portion of its reciprocation, and means for moving said gear from the plane of 30 one of said segments into the plane of the other of said segments for alternative engagements therewith.

9. In a printing press, in combination, a supporting frame, a reciprocating type bed having 35 a rack on the under side thereof, a rotary impression cylinder, driving mechanism including three shafts supported in said frame with their axes in substantially the same horizontal plane, the axis of the middle shaft being substantially 40 vertically under the axis of said cylinder, a gear on said middle shaft meshing with said rack, a pair of equal size intermeshing gears on said outer shafts located outside said frame, a gear segment on each of said outer shafts disposed in 45 different planes and between said meshing gears and said frame and each rotatable with one of said meshing gears, a gear splined on said middle shaft outside said frame, and means to move said splined gear from the plane of one of said gear 50 segments into the plane of the other for alternative engagements therewith.

10. A bed motion for a printing press of the two revolution type provided with a frame and a reciprocating bed thereon adapted to execute a 55 forward printing stroke and a reverse idle stroke, including, in combination, a pair of gear segments rotatively mounted adjacent each other on the frame, the axes of said segments being in the same horizontal plane, each of said segments being of an angular extent of 240°, means for rotating said segments in opposite directions at the same constant angular velocity, at the rate of two revolutions for each complete cycle 60 of reciprocation of said bed, and means alternately driven by said segments and operatively connected with said bed for effecting reciprocation of the same at a uniform velocity for more than one-half of each stroke including an axially 65 slidable gear with its axis in the same plane as the axes of said segments.

WILLIAM M. KELLY
